(57) **CLAIM**

The ornamental design for a trolling motor head unit, as shown and described.

DESCRIPTION

FIG. 1 is a front, top perspective view of a trolling motor head unit of the present design;

FIG. 2 is a front, bottom perspective view of the trolling motor head unit of FIG. 1;

FIG. 3 is a front view of the trolling motor head unit of FIG. 1;

FIG. 4 is a rear view of the trolling motor head unit of FIG. 1;

FIG. 5 is a left side view of the trolling motor head unit of FIG. 1;

FIG. 6 is a right side view of the trolling motor head unit of FIG. 1;

FIG. 7 is a top view of the trolling motor head unit of FIG. 1;

FIG. 8 is a bottom view of the trolling motor head unit of FIG. 1; and,

FIG. 9 is a right side view of the trolling motor head unit of FIG. 1 shown in a state of use, attached to a trolling motor shaft and cord.

The uneven broken lines immediately adjacent the shaded area(s) represent the bounds of the claimed design while all other broken lines represent portions of the trolling motor head unit or environment that form no part of the claimed design.
